UNITED STATES PATENT OFFICE

LOUIS DEL TURCO, OF NEWARK, NEW JERSEY

METHOD AND MEANS FOR SECURING TREADS TO STEEL SUBTREADS

Application filed January 24, 1930. Serial No. 423,052.

This invention relates to a novel method and means for securing treads such as those made of terrazzo, stone, slate, marble and the like, to the pressed steel sub-treads of a constructed stairway.

One of the objects of this invention is to provision of a method and means for securing to a preconstructed pressed steel stairway a plurality of such treads.

10 Another object of this invention is the provision of a method and means for rigidly securing, against warping, a plurality of treads to the metal framework of a preconstructed stairway.

15 Various other objects and advantages of the invention than those hereinabove mentioned will appear more fully hereinafter. It is to be understood that the specific forms shown are merely illustrative and hence the 20 detailed description thereof is not to be taken as limiting the invention itself.

In the art of creating marble-like stairways formed of a plurality of treads, or, as is known in the trade, non-slip alundum aggregate treads, difficulty has been encountered in the provision of a method and means for securing such aggregate treads to a metal framework stairway when in the condition left by the iron workers. This difficulty not 25 only has been encountered with respect to the aggregate treads mentioned, but has been found to prevail when treads of stone, slate, marble and the like have been used. I, therefore, propose to delineate a method whereby 30

35 any type of tread may be secured to a sub-tread, and I do not intend to limit myself to the provision of a method and means for the securing of merely aggregate treads to sub-treads. The treads as usually made and 40 brought on to the job are completed articles, having been manufactured in the shop, and when delivered to a particular building for use therein are in properly seasoned condition and polished. The difficulty encountered 45 usually arises when attempt is made to secure such finished treads in a neat non-warpage and inconspicuous fashion. It is possible to drill holes through the ends of such treads and through the steel subtreads, pass screws therethrough and secure such

treads to the subtreads by bolting. Such method, however, although it would prevent the undesirable warping of the ends of the tread away from the sub-tread would have a very inartistic effect. To eliminate such 55 undesirable effect constitutes one of the purposes of this invention which is to provide a cheap, rugged method and means of securing treads to a metal stairway in a manner whereby the securing means do not impair the artistic effect.

Referring now to the drawings, it will be seen that in:

Figure 1 is a perspective view of a stairway showing my novel structure;

Fig. 2 is a front elevational view of the stairway shown in Figure 1;

Fig. 3 is a bottom view of a metal step partially broken away;

Fig. 4 is a sectional view taken along the 70 line 4-4 in Figure 1;

Fig. 5 is an enlarged partially broken sectional view of one end of the tread shown in Fig. 4;

Fig. 6 is a sectional view taken along the 75 line 6-6 of Fig. 5;

Fig. 7 is a broken perspective view of my dovetail unit;

Fig. 8 is a broken perspective view of my adjustable securing flanging;

Fig. 9 is a variant embodiment of the construction shown in Fig. 5;

Fig. 10 is a second variant embodiment of the construction shown in Fig. 5.

Similar reference characters refer to similar parts throughout the various views.

Referring now to the figures, it will be seen that at 1, I show the under face of a pressed steel subtread of a metal preconstructed stairway having at 2 a riser running upward to the next higher metal sub-tread, and at 3 a riser dropping downward to the next lower sub-tread. This metal sub-tread is drilled at four points, two holes at either end thereof to receive therethrough machine screws or toggle headed screws 4, 4, 4, 4. When the underside of the stairway is accessible and headed screws can be slipped into the drill holes from under the stairway ordinary machine screws may be used. However, when the un-

derside of the stairway is inaccessible, after the holes are drilled, collapsible toggle headed bolts are inserted from the upper face of said sub-tread through the bolt holes. When 5 the heads of such toggle bolts expand beneath the stairway they accomplish the same function as the ordinary machine screw head. At 9 the metal sub-tread there is placed a securing flanging 5, such as is shown in Fig. 10 8, having slots 6, 6 therein. The shape of such flanging may be, as is shown in Fig. 8, of a generally L-shape with the elongated side of the L laid against the flat surface of the upper side of the sub-tread. The slots 15 6, 6 render the flanging 5 adjustable side- wise on the screws or bolts 4, 4. When the proper adjustment of such securing flanging is attained nuts 7, 7 are tightened down on each of said screws or bolts 4, 4 and thus the 20 securing flanging is secured to the upper face of the metal sub-tread with the shorter leg of the L-shaped flanging rising up, as is shown in Fig. 5 at 8. When each pressed steel metal sub-tread 1 has mounted thereon two of these 25 securing flangings 5 the metal sub-tread is then in a condition to have mounted thereon a properly manufactured aggregate tread, 11. These aggregate treads, designed for such mounting are actually re-enforced with 30 a plurality of re-enforcing bars 9, 9, 9 and while still in a plastic state have mounted therein at either end thereof metal dovetails 10, such as are shown in Fig. 7. The object of such metal dovetails is to form the cementitious block on its underside and at either end thereof before hardening into a dovetail shape. The metal form which is 35 pressed into the cementitious material might be removed therefrom after the material has taken its form, but it has been found more 40 expedient from the viewpoint of commercial success and cost to leave such metal dovetails which are of cheap metal, positioned in place after hardening. The metal dovetail 45 may extend from the rear face of the tread almost to the front nosing of the treads beneath the re-enforcing bars and be made inconspicuous at the front nosing of the tread by filling in all exposed portions thereof 50 after the tread is mounted as a unit upon the sub-tread. If, instead of using a tread originally composed of plastic material which, 55 when hardening, will set and contain therein the metal dovetail forms, the tread that is used be of stone, slate or marble, I accomplish the provision of dovetail indentations in such stone, slate or marble tread by cutting out, by hand or machine, the material to give such indentations rather than by 60 forcing the metal dovetail form into the plastic material, as I have heretofore recited. Since it is, of course, immaterial how the tread obtain the two dovetail indentations requisite to this invention, I deem that this 65 cutting out of the dovetail indentation is the

equivalent of the forming of such indentation in the tread material of an originally plastic tread. The completed tread of terrazzo material, or the like, having at either end thereof one of the formed dovetail indentations is, after being polished and seasoned, ready for mounting upon the metal sub-tread which has secured thereto the L-shaped metal securing flanging. All that is then necessary to effect such securing of the tread to the flanging is to spread upon the upper face of the metal sub-tread with a trowel a layer of cementitious mixture, 12, which fills the loop of the L, the dovetail indentations on the under face of the sub-tread and provides the body thickness 12 of cementitious material between the under face of the tread generally and the upper face of the sub-tread. When such filling material is inserted within the dovetail shaped indentations and within the preshaped metal securing flanging the effect will be that upon the hardening of such securing cementitious material a cement dovetail will be formed which is secured to the upper face of the sub-tread by the L-shaped metal securing flanging and to the tread at the dovetail joint. 70 75 80 85 90 95 100 105 110 115 120 125 130

It is, of course, apparent that the securing flanging need not be of the single L type shown in Fig. 5, but may be of a type wherein the L joint is duplicated as shown in Fig. 9. Such mounting would necessitate, of course, the provision of eight bolt holes and eight screws and nuts on each sub-tread. The securing effect would be increased by the duplicating of such securing flanging, and on jobs where the time spent in securing the flanging such as 5a—5a would not be prohibitive it is possible that this variant embodiment may be beneficially used. A further embodiment of securing flanging which would necessitate a still greater degree of adjustment before being ultimately secured to the upper face of the metal sub-tread is that shown in Fig. 10 of the U-type 5b. For this variant type of flanging but the usual two-bolt holes at either end of the metal sub-treads would be needed, and the holding effect would be duplicated and be substantially the equivalent of that shown in Fig. 9. It is apparent, however, that such type of securing flanging would necessitate the expenditure of more time in the mounting thereof and constitute a more expensive type of unit. It is believed to be apparent in all of the above types of securing flanging embodiments that it becomes necessary that the securing end of such flanging be allocated in every instance within the dovetail shaped indentation of the underside of the tread. It is, of course, therefore preferable that the dovetail shaped indentation be large enough so that when the tread is seated over the securing flanging but little adjustment there-

of will act to allocate the securing end of such flangings within such indentations.

As I have already described, the structure recited need not be limited in its application merely to terrazzo aggregate treads, but may be adapted to use with treads made of any commercial material used for such purpose, such as stone, slate, marble, and the like, in which case, of course, the necessity of a dovetail metal form is no longer present and such form can be dispensed with.

Further than this it is of course apparent that the dovetail shaped indentations and securing flangings need not be allocated so that

they run transversely of the treads but may be disposed in any direction across the surface of the treads and sub-treads which will either meet the mechanical needs of a given installation or secure a firmer holding effect.

When the size of a given installation requires that the treads be made in sections adapted to be joined together this possible variant disposition of the securing means in any pre-chosen direction is, of course, particularly advantageous in the securing of such sectional treads together by a common securing of each of the sectional treads to the sub-treads.

From the foregoing, it will be apparent that I have provided a relatively simple structure for carrying out the objects set forth above. I am aware that numerous changes in the details of construction and relative arrangement of parts will occur to those skilled in this art, and I do not, therefore, desire to be limited to the exact structure disclosed and illustrated by me, but rather to the scope of the invention as set forth in the appended claims.

What I desire to secure by United States Letters Patent is:

1. The method of securing a tread to a sub-tread which consists in forming a dovetail shaped indentation on the under surface of such tread, mounting a securing means on the upper face of the sub-tread and filling around said securing means and into said dovetail shaped indentation a cementitious material.

2. The method of securing a tread to a sub-tread which consists in mounting upon the sub-tread a securing flanging, forming an indentation in the tread, mounting said tread so that said indentation thereon registers with the securing flanging, mounting said tread on said sub-tread and filling said indentation with a cementitious material which surrounds said securing flanging.

3. The method of securing a terrazzo tread to a metal sub-tread which consists in forming a plurality of indentations on the under surface of said tread, mounting a plurality of securing flangings on the upper surface of said sub-tread and interposing be-

tween said securing flangings and said indentations a cementitious material.

4. In a structure substantially of the type described, a tread having allocated on the bottom thereof two dovetail shaped indentations, a sub-tread having therethrough a plurality of bolt holes, a securing flanging secured to the upper surface of said sub-tread by a plurality of bolts and nuts, said flanging being so allocated that the securing portion thereof falls within the confines of said indentation and a cementitious material surrounding said flanging and filling said indentation.

5. In a structure substantially of the type described, a tread having grooves therein, a sub-tread, means mounted on said sub-tread and seating in the grooves in said tread for permanently and rigidly securing said tread to said sub-tread.

6. In a structure substantially of the type described, a metal sub-tread, securing means mounted thereon, a tread having grooved indentations on the under surface thereof, and a binding material securing said tread to said sub-tread at said indentations.

7. In a structure substantially of the type described, a tread having a plurality of dovetailed indentations running transversely thereof, a sub-tread having mounted thereon a plurality of L-shaped securing flangings and a cementitious material securing said flangings to said tread at said dovetail indentations.

8. In a structure substantially of the type described, a tread having a plurality of dovetail shaped indentations running transversely thereof, a sub-tread having secured thereto on the upper surface thereof a plurality of U-shaped securing flangings adapted to register with said indentations, and a cementitious filling body adapted to secure said tread to said securing flangings at said indentations.

9. In a structure substantially of the type described, a sub-tread, a securing flanging adapted to be secured thereto, means securing said flanging to said sub-tread, and means including a preformed metal member mounted on said tread for securing said tread to said flanging.

10. The method of securing a tread to a sub-tread which consists in mounting upon the sub-tread a securing flanging, cutting an indentation in the tread, mounting said tread so that said indentation thereon registers with the securing flanging, mounting said tread on said sub-tread and filling said indentation with a cementitious material which surrounds said securing flanging.

11. In a structure substantially of the type described, a tread having a plurality of dovetailed indentations cut therein and running transversely thereof, a sub-tread having mounted thereon a plurality of securing

- flangings, and a cementitious material securing said flanging to said tread at said dovetail indentations.
12. In a structure substantially of the type described, a tread having transverse grooves therein, a sub-tread, means mounted on said sub-tread and seating in the transverse grooves in said tread for permanently and rigidly securing said tread to said sub-tread.
13. In a structure substantially of the type described, a tread, bars disposed in said tread to reinforce the same, a sub-tread, a securing flanging mounted on said sub-tread, means for securing said flanging to said tread, and means comprising collapsible head toggle bolts for securing said flanging to the sub-tread.
14. In a structure substantially of the type described, a tread, a sub-tread, an L-shaped flanging mounted on said sub-tread, and means for securing said flanging to said tread.
15. In a structure substantially of the type described, a tread having a dovetail indentation therein, a sub-tread, two opposed L-shaped securing flangings mounted on said sub-tread and disposed within the dovetail indentation, and means for securing said flangings to said tread.
16. In a structure substantially of the type described, a tread, a sub-tread, a securing flanging mounted on said sub-tread, said flanging being slotted for adjustability upon the means for securing it to the sub-tread, and means for securing said flanging to said tread.
17. In a structure substantially of the type described, a formed cementitious tread having a dovetail indentation therein, a rigid dovetail element disposed in said indentation, a sub-tread, a securing flanging mounted on said sub-tread, and means for securing said flanging to said tread.
18. In a structure substantially of the type described, a sub-tread, a tread extending beyond said sub-tread and having a dovetail shaped indentation therein, the exposed portion of which is filled in to present a smooth under side for said tread, a securing flanging on said sub-tread, and means for securing said flanging to said tread.
19. In a structure substantially of the type described, a sub-tread, a tread of greater width than the width of said sub-tread seated on said sub-tread and extending therefrom and having a nosing portion thereon which may be of various pleasing contours, and means for rigidly securing said tread to said sub-tread.
20. In testimony whereof I have hereunto set my hand on this 21st day of January A. D., 1930.

LOUIS DEL TURCO.
